UNITED STATES PATENT OFFICE

DOUGLAS R. RADFORD AND CHARLES LAMB, OF LOS ANGELES, CALIFORNIA

TWO-PIECE WEAR-PREVENTER

Application filed January 23, 1929. Serial No. 334,405.

Our invention relates to well-drilling equipment and relates particularly to wear-preventers for use on drill-pipe.

In the rotary system of drilling wells the rotary bit is attached to the lower end of a string of drill-pipe, which string of drill-pipe is rotated by a rotary machine situated on the floor of the derrick of the well. The drill-pipe consists of stands of pipe which are connected together by tool joints. Each stand is about eighty feet long and consists of four lengths of pipe which are attached together by ordinary sleeve-couplings. Since the extreme length of the drill-pipe renders it comparatively flexible and since the well is usually crooked the tool joint portions of the drill-pipe will engage one side of the well-casing or one side of the well if no casing has been installed. This engagement causes wear on the drill-pipe and if a well-casing has been installed it causes wear on the well-casing.

To overcome these disadvantages and avoid wear on the drill-pipe and well-casing wear-preventers have been devised for installation on the drill-pipe. These wear-preventers consist of collars which are secured to the drill-pipe. The collars being larger than the drill-pipe engage the well-casing or the side of the well, and in view of this fact, wear on the drill-pipe is entirely prevented and wear on the well-casing is considerably reduced.

The ordinary wear-preventers are annular and extend entirely around the drill-pipe. Sometimes the wear-preventers are nearly as large as the well-casing or the hole in which the drill-pipe is operated. Consequently the flow of rotary fluid which is flowing upward through the well is hindered to the extent that the cuttings of the bit are not satisfactorily carried to the surface of the ground.

One of the objects of our invention is to provide a wear-preventer for drill-pipe which is so designed that it will not hinder the flow of rotary fluid through the well.

Another object of our invention is to provide a wear-preventer which is formed of opposing sections less than an annulus, which are offset along the axis of the drill-pipe so

that a large space is provided opposite each section.

Another object of the invention is to provide a wear-preventer of the character mentioned which is secured in place by an annular strap. 55

A still further object of our invention is to provide a wear-preventer which is secured in place by means which surrounds part of the wear-preventer and engages the part of the pipe opposite the wear-preventer. 60

A still further object of our invention is to provide a wear-preventer adapted to be placed on a drill-pipe, which wear-preventer includes a section adapted to engage the drill-pipe, this section having upper and lower channels, and has annular securing means extending around the drill-pipe and extending in the upper and lower channels of the section. 65

In the following description we shall point out other objects of our invention.

Referring to the accompanying drawing in which various embodiments of our invention are illustrated: 75

Fig. 1 is an elevational view showing one form of our invention in which the sections are offset.

Fig. 2 is a section taken on the line 2—2 of Fig. 1. 80

Fig. 3 is a view illustrating the form of our invention in which the sections are arranged opposite each other.

Figs. 4 and 5 are sections taken on the lines 4—4 and 5—5 of Fig. 3. 85

Fig. 6 is an elevational view of the third form of our invention.

Fig. 7 is a section taken on the line 7—7 of Fig. 6.

Fig. 8 is a section of another form of the invention. 90

Referring to the drawing we will describe the form of our invention illustrated in Figs. 1 and 2.

The numeral 11 represents a casing which has been installed in a well 12. The numeral 14 represents part of a drill-pipe which, according to standard practice, extends from the surface of the ground in which it is rotated by means of a rotary machine to the 100

bottom of the well where a rotary bit is secured to it, this bit rotating with the drill pipe and boring the well.

Our invention provides a section 16 which is less than an annulus. In the form shown the sections 16 are semi-annular but it should be understood that they may be greater or less than semi-annular, the important feature being that they are less than an entire annulus. The section 16 includes a central body portion 17 having an outer arcuated face 18 adapted for engagement with the well-casing 11. Extending upward and downward from the body 17 are walls 19. Formed at the outer ends of the walls are outwardly extending flanges 19a. This construction provides upper channels 20 and lower channels 21. The sections 16 are preferably made from an anti-friction material such as rubber. The sections need not be entirely made from rubber but should have those portions formed from rubber or rubber composition which engage the well-casing 11 or, in the event that no well-casing has been installed, the wall of the well 12.

In Fig. 1 we show two sections 16 which are offset along the axis A—A of the drill-pipe 14. The sections are placed in opposing relation so that the upper section is on the left side of the drill-pipe 14 and the lower section is on the right side of the drill-pipe 14. If more than two sections are provided the sections may be made less than semi-annular and may be arranged on radial center lines which are 120° apart rather than 180° apart, as illustrated in Fig. 1. Opposite the upper section 16 is a comparatively large space 22 and opposite the lower section 16 is a comparatively large space 23. Between the lower end of the upper section and the upper end of the lower section is a connecting space 24. The spaces 22, 23 and 24 provide a passage for the rotary fluid to pass through. The spaces are sufficiently large to not restrict the flow of rotary fluid upwardly through the well.

The sections are secured together by securing means which preferably rest in the channels 20. In Figs. 1 and 2 the securing means is shown in the form of completely annular straps 26. A strap 26 extends in the upper channel 20 and the lower channel 21. The straps 26 engage the drill-pipe on the side opposite from the section 16, as illustrated in Fig. 2. The section 16 is first placed as shown, whereafter the straps are placed as shown and then the ends of the straps are secured together as indicated at 27. Any suitable securing means may be provided. In the drawing the ends of the strap are bent into interlocking relation but it should be understood that separate fastening means may be provided, if desired.

The means for attaching the ends of the straps 26 must be such that the strap will be

placed under considerable tension so that the sections 16 will be securely clamped to the pipe so that they cannot rotate thereon.

It is not essential to the invention that the strap 26 be a complete annulus. For example, the strap 26 may be made in two parts, one end of each of the two parts being secured to the section 16. It seems desirable at the present time to make the strap 26 from a comparatively flexible material but it is within the broad concept of my invention to make the securing means 26 from a rather rigid material which does not have to be completely annular. For example, the securing means may be made in two pieces of rigid material which are secured together by bolts. Furthermore, it is not essential to the invention that the channels 20 and 21 be provided. This construction is adhered to only because it is convenient to the form of the invention illustrated in the drawing.

The form of the invention just described and illustrated in Figs. 1 and 2 will prevent the drill-pipe 14 from engaging the casing 11 or the wall of the well 12 and at the same time it will not prevent the rotary fluid from flowing through the well. The important part of the invention therefore rests partly in this feature. Another important feature of the invention is the means of attaching the sections 16 in place, which means provides a securing means adapted to engage the sections 16 and the part of the drill-pipe opposite the section 16.

In Figs. 3, 4 and 5, we show a form of our invention in which the sections 16 are placed opposite each other so that two sections provided an annulus. The straps 26 do not engage the drill-pipe 14 but rest in the pairs of upper channels 20 and lower channels 21. In this form of the invention the wear-preventer operates like an ordinary annular wear-preventer but is superior in the means and manner of securing the section 16 in place. The sections 16 are placed in the position shown in Fig. 3 and thereafter the straps 26 are secured in place.

In Figs. 6 and 7 we show a form of our invention in which the straps 26 are embedded in the walls 18. In this construction the straps are attached to the section 16 at all times and are easier to install for the reason that when the section is held in place the strap is readily available and the ends thereof may be secured together very quickly. In this form of the invention the strap 26 need not be in one piece but may be in two pieces which extend outward from edge faces 30 of the section. It is not essential to this form of the invention to have the channels 20 and 21.

The form shown in Fig. 8 includes a one-piece body 40 which is split at 41. The body is spread apart and placed on the pipe 14 and then the straps 26 are secured in place.

Before the straps are secured the body 40 is less than a cylinder, the edges being separated as shown by dotted lines 42.

We claim as our invention:

A wear-preventer adapted to be placed on a drill-pipe comprising: a section having a relatively extensive engaging surface adapted to engage said drill-pipe; and annular securing means surrounding said section and engaging said drill-pipe for securing said section in place.

In testimony whereof, we have hereunto set our hands at Los Angeles, California, this 16th day of January, 1929.

DOUGLAS R. RADFORD.
CHARLES LAMB.
